CARPET DISPLAY STAND

Ralph W. Wagoner, Naperville, Ill., assignor to Sears, Roebuck and Co., Chicago, Ill.

Filed Feb. 2, 1970, Ser. No. 21,191

Term of patent 14 years

Int. Cl. D6—01

U.S. Cl. D80—9

Fig. 2.

FIG. 1 is a front perspective view of a carpet display stand showing my new design; and

FIG. 2 is a rear perspective view thereof; and

FIG. 3 is a side elevational view thereof. The side not shown is substantially similar in appearance to the side shown in the drawings.

I claim:

The ornamental design for a carpet display stand, as shown and described.
